United States Patent Office

Des. 232,090

Patented July 16, 1974

232,090

PORTABLE HYDRANT

George G. Allenbaugh, Jr., Wadsworth, Ohio, assignor to
Premier Industrial Corporation, Cleveland, Ohio

Filed Oct. 20, 1972, Ser. No. 299,365

Term of patent 14 years

Int. Cl. D23—01

U.S. Cl. D23—12

Fig. 1

Fig. 2

FIG. 1 is a perspective view of a portable hydrant embodying my new design; and

FIG. 2 is a bottom plan view thereof.

I claim:

The ornamental design for a portable hydrant, substantially as shown.
